UNITED STATES PATENT OFFICE.

ALFRED FISHER, OF CHICAGO, ILLINOIS.

OIL-BURNER SYSTEM FOR FURNACES.

1,385,534.

Specification of Letters Patent. Patented July 26, 1921.

Application filed February 20, 1920. Serial No. 360,218.

To all whom it may concern:

Be it known that I, ALFRED FISHER, a citizen of the United States, and a resident of the city of Chicago, in the county of Cook 5 and State of Illinois, have invented certain new and useful Improvements in Oil-Burner Systems for Furnaces; and I do hereby declare that the following is a full, clear, and exact description of the same, reference being had to the accompanying drawings, and to the numerals of reference marked thereon, which form a part of this specification.

This invention relates to an improved type of an oil burner system wherein oil burners 15 are adapted to direct heating flames into a furnace firebox provided with a plurality of baffle plates so distributed and arranged that the flames are evenly divided to insure an even distribution of heat in all parts of 20 the firebox.

It is an object of this invention to provide an improved oil burner heating unit for furnaces.

It is also an object of the invention to 25 provide a furnace with an oil burner system adapted to direct flames against a series of baffle plates within the furnace firebox to insure a complete consumption of the oil blown into the firebox.

30 A further object of this invention is to provide a furnace firebox with a series of curved baffle plates which are so distributed that they will cause an even distribution of oil burner flames directed into the firebox.

35 It is an important object of this invention to provide an improved system for supplying oil and air to blast burners which are adapted to direct flames against firebox baffle plates to insure an even heating of the fur-

40 nace.

Other and further important objects of this invention will be apparent from the disclosures in the drawings and specification.

45 The invention (in a preferred form) is illustrated in the drawings and hereinafter more fully described.

On the drawings:

Figure 1 is an elevational view of a furnace oil burner system embodying the principles of this invention, showing a fragmentary portion of the furnace.

50 Fig. 2 is a fragmentary front view of the furnace showing the burner pipe connections.

Fig. 3 is a sectional view taken on line 3—3, of Fig. 2.

Fig. 4 is a sectional view taken on line 4—4, of Fig. 3.

Fig. 5 is an enlarged side elevation of one 60 of the oil blast burners.

Fig. 6 is a vertical longitudinal section thereof.

Fig. 7 is a section taken on line 7—7, of 65 Fig. 5.

As shown on the drawings:

The reference numeral 1, indicates a furnace, the front wall of which is provided with firebox openings which are closed by means of door plates 2, rigidly secured in 70 position. The furnace is provided with a firebox in the lower front portion thereof. The firebox embraces a fire-brick floor 3, supported on grate bars 4. Secured across the rear end of the fire-brick floor 3, are straight 75 vertical rear wall plates 5, made of fire-brick. Mounted on the firebox floor 3, between each of the door plates 2, and the wall plate 5, disposed to the rear thereof, are two rows of curved fire-brick baffle plates 6. Each 80 baffle plate 6, is curved or arc-shaped and has the front upper corner thereof cut away as at 7 to afford a deflecting edge. The baffle plates 6, of each row are aligned and spaced apart. The baffle plates 6, of one row 85 are mounted to diverge from those of an adjacent row to afford a passage longitudinally between each two rows of said spaced baffle plates. As clearly shown in Fig. 4, the rows of baffle plates are so arranged that 90 flames directed into the firebox passages are broken up by the diverging rows of baffle plates which serve to evenly distribute the flames in the furnace firebox.

Projecting into an opening in each of the 95 furnace door plates 2, is a blast burner adapted to direct oil-gas heating flames into the firebox for distribution by the rows of baffle plates 6. Each blast burner embraces a conical casing or twyer 8, having 100 a restricted nozzle 9, which projects into an opening in a furnace door plate. Disposed longitudinally within the twyer 8, is a hydrocarbon pipe 10, the inner end of which extends approximately to the restricted nozzle 105 9. The outer end of the pipe 10, is connected in a plug 11, and communicates by means of a valve 12, with an oil or other hydrocarbon supply or feed pipe 13.

Secured beneath and opening into the 110

- twyer 8, is a tubular air-regulating plug valve 14, of conical shape and provided with a side port or opening 15, for communication with the interior of the twyer as shown in Fig. 7. An air blast pipe 16, is connected with one end of the housing 17, of the plug valve 14. The other end of the air pipe 16, is connected with an air pump or blower 18, adapted to produce the desired blast-pressure within the furnace. An air valve 33, is provided in the pipe 16 near the air pump 18. Connected with the plug valve housing 17, is an air-relief pipe 19, the outlet to which is controlled by the plug valve 14. The other end of the air-relief pipe 19, is open to the atmosphere. The arrangement of said plug valve is such that when it is adjusted to admit the blast to the twyer 8, the relief pipe 19, is closed thereby. When the plug valve 14, is rotated to exclude the blast from the twyer or partly exclude the same, the blast or a portion thereof, is delivered through the relief pipe 19. This arrangement enables the force of the blast to be regulated to suit the requirements of use. A lever 20, is provided for engaging a squared head or tip 21, which is integrally formed on the closed end of the plug valve 14, and projects through an opening in an end plate 22, of said plug valve housing 17.
- One or more burners may be used. As shown two burners are employed one for each of the furnace door plates 2, to send the blast in the same direction into the furnace firebox. In this construction both of the burners are connected with the air pipe 16 and the oil or hydrocarbon pipe 13, to permit uniformity of action to be secured without difficulty. The air-relief pipes 19, may be connected to a common pipe to permit the blast to be discharged at any convenient distance from the furnace when the plug valve openings 15, communicate with the relief pipes 19.
- The oil pipe 13, is connected with a vertical pipe 23, the lower end of which is connected by means of pipes 24, to two pumps 25. Each pump 25, is independently driven by a motor 26. Each pipe 24, is provided with a control valve 27. As shown in Fig. 1, both pumps 25, are connected by means of pipes 28, to a common feed pipe 29, which is connected to an oil or hydrocarbon tank 30. Each pipe 28, is provided with a control valve 31. The supply pipe 32, is attached to the tank 30, to supply kerosene oil or any other suitable hydrocarbon fuel to said tank.
- Mounted on the upper end of the pipe 23, is a cross or four-way connector 34. Connected with the upper arm of said connector 34, is the lower end of an auxiliary oil or hydrocarbon tank 35. A pressure gage 36, is mounted upon the auxiliary tank 35. The

side arms of the connector 34, are connected with pipes 37, each of which has a control valve 38, connected therein. The pipes 37, both connect up with one end of an overflow pipe 39, the other end of which is connected with the top of the main tank 30. Connected between the oil pump platform 40, and the main overflow pipe 39, is an auxiliary overflow pipe 41, provided with a valve 42.

75 The operation is as follows:

With the oil and air supply system connected up with the blast burners mounted on the furnace 1, said furnace is adapted to be rapidly and evenly heated by flame blasts 80 from the burners. To start the system one of the pipe valves 31, and the corresponding valve 27, are opened. The respective pump 25, connected with said valves, is now operated by its motor 26, thereby causing oil 85 from the main tank 30, to be pumped through the pipes 23 and 13, into and through the two blast burner oil pipes 10. By starting the air pump 18, and opening the air pump valve 33, air is blown through 90 the air pipe 16, into both of the twyers 8, when the plug valves 14, are turned into the position shown in Fig. 7. The blasts of air and oil mix in the burner nozzles 9, and are blown into the furnace firebox and ignited. 95 The blast flames thus entering the furnace firebox pass rearwardly through the passages between the double rows of the baffle plates 6. The peculiar shape and arrangement of the baffle plates 6, cause the blast 100 flames to hit against the curved baffle plate edges 7, and then follow the curved shape of said baffle plates. The blast flames are thus broken up or distributed evenly within the furnace firebox resulting in an even heating of the furnace. The intensity of the blast flames may be controlled by adjusting the plug valves 14 and the oil valves 12. When the plug valves 14, are rotated to exclude the air from the twyers 8, the air blast 110 is delivered through the air-relief pipes 19. The force of the blast may thus be regulated to suit the requirements of use.

115 Oil under pressure from the pump 25, also enters the auxiliary oil tank 35, and flows into the pressure gage 36, which indicates the pressure of the oil being supplied to the blast burners. When the oil pressure becomes too great the respective valve 38, is opened to permit part of the oil from the pump to return to the main tank 30, through the overflow pipe 39.

120 If at any time one of the oil pumps 25, should get out of order, the valves 27 and 31, for said pump are closed, and the other or emergency oil pump may be connected in the system by opening the valves 27 and 31, of said emergency pump. Any oil which may leak from the pumps 25, onto the platform 40, is permitted to return to the main 125 130

oil tank 30, by way of the auxiliary over-flow or return pipe 41, when the valve 42, is open.

I am aware that numerous details of construction may be varied through a wide range without departing from the principles of this invention, and I therefore do not purpose limiting the patent granted otherwise than necessitated by the prior art.

10 I claim as my invention:

1. In a furnace the combination with the furnace firebox, of blast burners mounted to direct flames into said firebox, and a plurality of rows of curved upright baffle plates mounted on the firebox floor, each of said baffle plates having one of the corners thereof cut away to afford a curved deflecting edge.

2. In a furnace the combination with the furnace firebox, of blast burners mounted to direct flames rearwardly into said firebox, straight baffle plates across the rear end of the firebox floor, and a plurality of parallel rows of notched outwardly curved upright baffle plates disposed in the firebox to provide a series of branching side passages leading from main passages whereby the flames from said blast burners are evenly deflected to all parts of the furnace firebox.

3. The combination with a furnace and the firebox thereof, of door plates rigidly secured in place to close the firebox door openings, blast burners mounted to project through the door plates, an air pipe connected with said blast burners, an air pump connected with said air pipe to blow air therethrough and into said burners, an oil

pipe also connected with said burners, an oil pump connected with said oil pipe, a main oil tank, piping connecting the same with said oil pump, an auxiliary oil tank also connected with said oil pipe, a pressure gage on said auxiliary oil tank, and an over-flow pipe connected with said auxiliary oil tank and with said main oil tank.

4. The combination with a furnace, of blast burners mounted thereon to direct flames thereinto, an air pump, an air pipe connecting said air pump with said blast burners, an air valve in said air pipe to control the flow of air from said air pump, a main oil tank, a main oil pump and an emergency oil pump, motors for independently driving said oil pumps, pipes connecting said oil pumps with said main oil tank, valves in said pipes, outlet pipes leading from said oil pumps, valves therein, a connecting pipe connected with said oil outlet pipes, an auxiliary oil tank connected with said connecting pipe, a pressure gage mounted on said auxiliary oil tank, an oil over-flow piping connecting said auxiliary oil tank with said main oil tank, valves in said overflow piping, and a burner oil supply pipe connected with said connecting pipe and with said blast burners.

In testimony whereof I have hereunto subscribed my name in the presence of two subscribing witnesses.

ALFRED FISHER.
